UNITED STATES PATENT OFFICE.

JAMES DRONSFIELD, OF OLDHAM, ENGLAND.

MACHINE FOR STRIPPING THE WASTE YARN LEFT ON CONDENSER-BOBBINS.

1,274,522.

Specification of Letters Patent.

Patented Aug. 6, 1918.

Application filed December 20, 1917. Serial No. 208,075.

To all whom it may concern:

Be it known that I, JAMES DRONSFIELD, a subject of the King of Great Britain and Ireland, residing at the Atlas Works, Oldham, in the county of Lancaster, England, have invented new and useful Improvements in Machines for Stripping the Waste Yarn Left on Condenser-Bobbins, of which the following is a specification.

10 This invention relates to a machine for stripping or removing the residuum waste condenser yarn left on condenser bobbins, which bobbins as is known are of considerable size. Such bobbins usually consist of 15 a wooden body with metal ends.

The attached drawings sufficiently illustrate the construction of my condenser bobbin stripping machine.

In the said drawings—

20 Figure 1 shows a rear elevation with certain of the parts in section and with the supports, &c., broken away.

Fig. 2 is an end elevation.

Fig. 3 shows a section.

25 Fig. 4 is an enlarged sectional elevation of the gearing end of the machine, while,

Fig. 5 shows a further sectional elevation taken at right-angles and on the line A—B, Fig. 4.

30 In my bobbin stripping machine I use end standards *a*, *a*, or other suitable supports, which carry a trough shaped bed *b* adapted to receive a longitudinally arranged table or condenser bobbin rest *c* of suitable kind.

35 The bobbin table or rest *c* illustrated is of cast metal and has an inclined top *c'* sloping downward from the back to the front edge *c''* and with trued ledges *c'''* at each end. Such table *c* is adjustably or otherwise se-

40 cured and ready means may be provided for ease in setting-up. Working in connection with such table *c* I employ a stripper device which takes the form of a cylinder *d* mounted on the shaft *d'* and covered with card wire, teeth, or such like, the same being supported in bearings such as bearings *d'', d'''*, and driven in any appropriate fashion either direct or through gearing.

45 The condenser bobbin *e* to be cleared is placed on the inclined top of the table *c* and so rolls or can be rolled toward the stripper device, the flanges on the bobbin due to the planed ledges *c'''* holding the same against end movement while the stripper device does its work.

In order to keep the cylinder *d* or strip-

per device effective for the object in view, it is necessary to comb the stripper device as same rotates and this I do by a rotary comb combination which forms part of the 60 machine and which I prefer to mount below the stripper device. The rotary comb combination consists of a slotted shell or tube *g* the end supports of which are mounted in one set of bearings *g', g'*, and, of a 65 shaft *h* which passes longitudinally through said slotted shell or tube *g* and is supported from another set of bearings *h', h'*, such shaft *h* having an applied comb or a line of spikes or comb teeth *h''* capable of emerging 70 from and receding through the slot in the shell or tube *g*. The bearings *g', g'*, *h', h'*, for the slotted shell or tube and the shaft with the comb teeth do not coincide, that is, the axial or center lines are not the same 75 (see Figs. 1 and 4). I drive the slotted shell or tube *g* from the shaft *h* carrying the comb teeth, and this may be done by an accommodating coupling device as for instance abutting flanges or plates *h'''* *g'''* may serve as the 80 driving connection, the flange or plate *g'''* carrying a die *g''* centered at *g'''* and which die engages a slot *h''* in the other flange or plate *h'''*. The flange or plate *h'''* is fixed on the shaft *h* by a key *h''*. Such a construction 85 insures that the slotted shell or tube *g* and the shaft *h* with comb teeth *h''* revolve at the same speed, but, during rotation, the teeth are advanced and withdrawn through the slot in the shell or tube *g* thus enabling the 90 slotted sleeve *g* to strip the fiber from the comb teeth. More than one set of teeth may be provided and the accommodating inter-connecting device may be varied and the slotted sleeve or tube may drive under 95 a modified form.

The slotted sleeve or tube *g* and the comb shaft *h* are driven at a high speed so that the comb performs its function a number of times for each revolution of the stripping 100 cylinder or device *d* and thus effectively strips or clears the latter.

I may considerably vary the driving arrangement, but, at present, I drive the comb shaft *h* direct through a fast belt pulley *i* 105 and the slotted sleeve or tube *g* in unison, through the coupling device before described.

Upon the comb shaft *h* is mounted a worm *j* secured by a key *j'* and this worm *j* actuates a worm wheel *k* on a short upright shaft *l* which carries a worm *m* gearing with a

worm wheel *n* on the shaft *d'* of the stripping roller or cylinder *d*. The entire worm gears are inclosed in a detachable casing *o* as shown which is made in one or more parts 5 and is secured by fixed studs and nuts *o' o'*. The loose pulley in the fast and loose pulley group is marked *i'*, and, the sliding bar *q* is the strap shifting device.

A detachable or other protecting canopy *p* 10 is fitted in connection with the stripping cylinder *d*.

The machine is easy to manage and simple in operation.

The bobbins to be stripped are placed in 15 turn on the inclined table *e*, and the wound-on fiber comes under the action of the card teeth on the stripping cylinder *d* which rapidly strip off the fibrous material, the stripping cylinder being quickly and continuously combed and the droppings deposited 20 on the floor or dropped into a receptacle.

The machine can be run at a high speed because the comb shaft and slotted sleeve are well balanced and each runs on its own 25 bearings.

So far as I am aware it is new to provide a machine to strip condenser bobbins and therefore I do not wish to limit myself with regard to any particular combination for the 30 end in view so long as the result is achieved on lines substantially similar to what I have outlined above.

I declare that what I claim is.

1. A machine for stripping waste yarn 35 from flanged condenser bobbins having in combination an inclined bobbin support, flange engaging edges thereon, a rotating toothed cylinder, a comb shaft with teeth, a slotted tube around said comb shaft, an axle 40 support for said slotted tube, bearings for the comb shaft, non-coinciding and independent bearings for the axis of the slotted tube, and an accommodating coupling device for the comb shaft and the slotted tube 45 permitting the one to be driven from the other and gear wheels to drive the toothed cylinder as set forth.

2. A machine for stripping waste yarn 50 from flanged condenser bobbins, having a bobbin feeding table, edges on said table

against which the flanges of the bobbins can bear, a rotating toothed cylinder, supporting means for said cylinder, driving gear therefor, a canopy for said cylinder, a rotating comb device, a slotted tube surrounding 55 said rotating comb device and adapted to clean the rotating comb device, independent bearings for the rotating comb device and the slotted tube and an accommodating coupling between the rotating comb device and the slotted tube, all in combination and as described.

3. In a machine for stripping waste yarn from condenser bobbins having flanges, a 60 bobbin support guiding said bobbin, guiding ledges thereon for coöperation with said flanges, an independent rotating toothed cylinder, means for driving said cylinder, a cylinder clearing device comprising a slotted tube, a comb shaft within said slotted tube, 65 teeth on the comb shaft, a set of bearings for the comb shaft, an independent non-coinciding set of bearings for the slotted tube, an accommodating coupling device interconnecting the comb shaft and slotted tube and 70 gear wheels for driving the rotating parts as set forth.

4. A machine for stripping waste yarn from flanged condenser bobbins, comprising 75 an inclined bobbin feeding table, ledges thereon for coöperating with the flanges of the bobbins, an independent rotating toothed cylinder in juxtaposition to such table, bearings in the machine therefor, a canopy for 80 said rotating toothed cylinder clearing combination, comprising a comb shaft, teeth thereon, a slotted tube surrounding said comb shaft, bearings for the comb shaft, independent non-coinciding bearings for the 85 slotted tube, an accommodating coupling device between comb shaft and slotted tube, 90 all in combination and for the purpose described herein.

In testimony whereof I have signed my name to this specification.

JAMES DRONSFIELD.
